UNITED STATES PATENT OFFICE.

JOHN FOERST, OF BAYONNE, NEW JERSEY.

BURNER.

1,321,816.

Specification of Letters Patent. Patented Nov. 18, 1919.

Application filed April 16, 1919. Serial No. 290,574.

To all whom it may concern:

Be it known that I, JOHN FOERST, a citizen of the United States, residing at Bayonne, in the county of Hudson and State of

5 New Jersey, have invented certain new and useful Improvements in Burners, of which the following is a specification, reference being had therein to the accompanying drawings.

10 This invention relates to improvements in burners and more particularly in burners employed for combustion of oil or gas preferably in steam-boilers, although the invention is equally adapted for use with various 15 other apparatuses of a similar character.

The invention has for its primary object to highly increase the efficiency of burners of this type and nevertheless construct the burner in the simplest manner possible, 20 thereby reducing the cost of production and its liability to get out of order.

In hydrocarbon burners it is basic that the greatest efficiency is obtained by proper atomization of the fuel employed or, in other 25 words, by dissociating the fuel particles to the extent producing a flame having a substantially constant heating capacity throughout by a simultaneous combustion of all the fuel particles.

30 In the present invention this ideal condition is closely approximated by obviating fitful and wasteful combustion in the manner hereinafter set forth in greater detail and referred to in the appended claims.

35 In the accompanying drawings, Figure 1 is a side elevation of a burner embodying the present improvement. Fig. 2 is a top plan view of the same. Fig. 3 is a sectional view in elevation of the burner. Fig. 4 is 40 a front end view of the same. Fig. 5 is a detail sectional view on the line 5—5 of Fig. 3 and Fig. 6 is a diagrammatic view illustrating the inclinations of the stream-controlling surface.

45 Referring to the drawings, the burner is preferably constructed of a casting 1 having a fuel chamber 2 and a chamber 3 for an atomizing agent such as steam or compressed air.

50 The fuel and the atomizing agent may be conducted to the chambers 2 and 3 by means of feed-pipes 4 and 5 suitably threaded into the casting 1. Near the delivery end, the fuel is led through a narrowed orifice 6 forming 55 a continuation of and projecting substantially at right angles to the length of the

chamber 2. The orifice 6 terminates in a flame controlling surface 7, intersecting the rear vertical wall 8 of the orifice for the chamber 3. The surface 7 is substantially horizontal from the wall 8 to the point *a*, and is slightly inclined downwardly from this point to its front free edge *b*. The surface 7 between the inner edge *c* of the orifice 6 and the front edge *b* is also slightly inclined downwardly from a central line toward the side edges 10 and 11. These relative inclinations of the surface 7 are clearly illustrated in Figs. 4 and 6 of the drawings and form an important feature of the present invention as will be later explained.

The chamber 3 terminates in an orifice substantially circular in the vertical plane containing the wall 8, as shown by the dotted line in Fig. 4. In advance of this wall 8 75 the lower portion of the orifice is cut away leaving an overhanging wall 12 curved downwardly toward the edge 13 and also transversely thereof toward its side edges 14 and 15 to form a narrowed stream-controlling 80 opening. The edge 13 is located rearward of the front surface 16 of the casting and between the two there is provided a segmental opening 17 the size of which, to a considerable extent, controls the length of the 85 flame. Adjacent the side edges 14 and 15 and slightly spaced therefrom the casting 1 is formed with upwardly projecting lugs, as 18, for a purpose about to be described.

Fuel conducted into the chamber 2 90 emerges through the orifice 6 substantially at right angles to the surface 7. An atomizing agent conducted into the chamber 3 tends to emerge in a fan-tail shaped stream along the surface 7, as indicated by dotted 95 lines in Fig. 2, the extent of the lateral spread being to some extent controlled by the length of the lugs 18. These lugs 18 also permit a slight suction of air to aid combustion. This tendency to spread out in 100 fan-shape is due to some extent to the shape of the overhanging wall 12 as will be readily understood. When the atomizing agent strikes the downwardly inclined surface 7, its plane of spread is correspondingly 105 inclined. The atomizing agent now strikes the upwardly rushing fuel, dissociating the particles of the latter and carrying them along with it. The fuel is now spread in fan-tail shape by the inclination of the surface 7 toward its side walls. With burners 110 of this type, the flame produced is often of

a considerable length and owing to the draft, present in the boiler, has a tendency to curl upwardly along its edges thereby passing between the boiler tubes and wasting the heat. By downwardly inclining the surface 5 toward its front and side edges, the flame receives an initial downward direction sufficient to produce a parabolical shape which under the contrary action of the draft 10 vents the edges of the flame from shooting upwardly in tongues and causes the edges to double upon themselves whenever there is a tendency to curl at the edges.

It will be observed that the edge *c* of the 15 orifice 6 is in a higher plane than its parallel edge, with the advantage that back-firing is obviated by the tendency to carry the fuel away from the orifice 6.

Having thus set forth the nature of the 20 invention, what I claim herein is—

1. In a burner, the combination with a frame provided with a fuel chamber and an atomizing-agent chamber, and means for conducting fuel and an atomizing agent 25 into said respective chambers, of a stream-controlling surface inclined downwardly toward its front edge and from a substantially median line toward its side edges, a fuel delivery orifice terminating in said stream- 30 controlling surface, and a delivery orifice formed in said atomizing-agent chamber.

2. In a burner, the combination with a frame provided with a fuel-chamber and an atomizing-agent chamber, of a stream-controlling 35 surface provided in said frame, a narrowed fuel-delivery orifice projecting substantially at right angles to and terminating in said stream-controlling surface,

the rearward edge of said orifice lying in a higher plane than the advance edge thereof, 40 and an atomizing-agent delivery-orifice overhanging said stream-controlling surface and formed with a substantially central segmental opening.

3. In a burner, the combination with a frame provided with a fuel-chamber and an atomizing-agent chamber, of a stream-controlling surface provided in said frame, a fuel delivery orifice projecting substantially at right angles to and terminating in said 50 surface, and an atomizing agent delivery orifice formed by a wall overhanging said surface, said stream-controlling surface and said overhanging wall being inclined toward their front and side edges for a purpose substantially as set forth.

4. In a burner, the combination with a frame provided with a fuel chamber and an atomizing agent chamber, and means for conducting fuel and an atomizing agent 60 into said respective chambers, of a stream-controlling surface inclined toward its front edge and from a substantially median line toward its side edges, a fuel-delivery orifice extending at a substantial angle with respect 65 to said stream-controlling surface, and a delivery orifice for the atomizing agent terminating rearwardly of said fuel-delivery orifice adapted to direct said atomizing agent upon said surface in a direction substantially transverse to the lead of the fuel from its delivery orifice.

In testimony whereof, I have signed my name to this specification.

JOHN FOERST.
